UNITED STATES PATENT OFFICE.

FREDERICK RAPP, OF CHICAGO, ILLINOIS.

DESIGN FOR A WATCH-CASE.

SPECIFICATION forming part of Design No. 17,616, dated August 9, 1887.

Application filed July 11, 1887. Serial No. 244,028. Term of patent 14 years.

To all whom it may concern:

Be it known that I, FREDERICK RAPP, a citizen of the United States, residing at Chicago, in the county of Cook and State of Illinois, have invented a new and original Design 5 for Watch-Cases, which is fully set forth in the following specification, reference being had to the accompanying drawing, forming a part hereof.

10 My design for a watch-case is in the form of a butterfly with folded wings resting upon a twig. Said twig is bent into a ring, which forms the pendant at the rear end of the body of the insect, and extending over or between 15 the outer edges of the wings, and there pro-

vided with leaves and flowers, which more or less hide and ornament the watch-case center between the wings of the insect.

The essential feature of my design is a butterfly with folded wings resting upon a twig 20 formed into a pendant.

What I claim is—

The design for a watch-case, the same consisting of the representation of a butterfly resting upon a twig formed into a pendant, as 25 described and shown.

FREDERICK RAPP.
